UNITED STATES PATENT OFFICE.

JOHN S. GOLDSMITH, OF NEW YORK, N. Y.

CHEROOT, CIGARETTE, AND CIGAR BUNCH MACHINE.

SPECIFICATION forming part of Letters Patent No. 339,403, dated April 6, 1886.

Application filed October 15, 1885. Serial No. 179,992. (No model.)

To all whom it may concern:

Be it known that I, JOHN S. GOLDSMITH, a citizen of the United States, residing at New York, in the State of New York, have invented 5 a new and useful Improvement in Cheroot, Cigarette, and Cigar Bunch Machines, of which the following is a specification.

This invention relates to machinery or mechanical appliances for making cheroots, 10 cigarettes, and cigar-bunches, and to that class of such devices in which the ordinary hand-method of "rolling" is followed or imitated.

Various styles of machines have been devised for doing such work, including a sub-class known in the Patent Office as "stationary-belt" machines, in which one end of each rolling-apron or "belt" is relatively stationary during the rolling operation. The other end of the apron is pulled and the tobacco is 20 rolled in a bight thereof by the aid of a suitable "check-piece" or "shaping-bar," by which the bight is closed. Previous to this invention such machines have never been so organized as to work more than one rolling-apron in each machine, and their tension-springs for giving a proper yielding resistance to the compression of the tobacco, when such have been employed, have been applied to the relatively stationary end of the apron, 25 with, in one instance, supplemental springs above the shaping-bar.

The present invention consists in an improved stationary belt-machine embodying several novel combinations of parts and features of construction, as hereinafter set forth and claimed.

Its several objects are as follows—viz: to enable each operator to "roll" several cheroots, cigarettes, or cigar-bunches, in place of 40 but one, at each operation; to facilitate making ready by placing the wrapper and tobacco in position preliminary to the rolling operation; to insure uniformity of shape in each kind of product; to insure uniformity of density or tightness in each kind of product; to provide for making cheroots and cigarettes or cigarettes and cigar-bunches by means of one set of shapers; to provide for applying the requisite strain to the free ends of the several 45 "aprongs" along the entire edge of each, with uniformity, without bulky parts; to provide for steadily pulling on the metallic cross-bars

of triangular section employed for this purpose; to provide for pulling the several aprons either obliquely, for making cheroots, or evenly for making cigarettes and cigar-bunches; to preclude interference between the aprons and shapers above them; to provide for extending the series of aprons, shapers, and appurtenances laterally as well as longitudinally; 55 and, finally, to reduce to a minimum the hand-work of the operator, so as to cultivate carefulness and skillfulness in those operations best performed by hand, to which the hand-work is confined.

Four sheets of drawings accompany this specification as part thereof.

Figures 1 and 2, Sheet 1, represent, respectively, a side view and a plan partly in section, of a cheroot, cigarette, and cigar bunch machine illustrating this invention, showing its shapers adjusted for making cheroots, and its parts as they appear in two successive stages of making ready; and Figs. 1^a, 1^b are edge views of one apron and its cross-bar on a 70 larger scale, with the latter in its respective preliminary positions. Figs. 3 and 4, Sheet 2, are a side view and a plan of the same machine, showing its parts by full and dotted lines as they appear at the beginning and end 75 of the rolling operation. Figs. 3^a, 3^b are large scale edge views of one apron, its cross-bar, and a corresponding shaper, with the cross-bar and shaper in the respective positions represented in Figs. 3 and 4. Fig. 5, Sheet 3, is 80 a top view of one of the rolling-aprons and its cross-bar. Fig. 6 represents a section thereof on the line 6 6, Fig. 5, and Fig. 6^a a like section, showing certain modifications. Fig. 7 represents a vertical transverse section 85 through one of the rolling-beds, and a doubled apron on the line 7 7, Fig. 2. Fig. 8 represents a longitudinal section on the line 8 8, Fig. 7, and Fig. 9 is a perspective view of the rear end of the pull-rod frame. Fig. 10, Sheet 90 4, represents a vertical transverse section through the upper part of the machine on the line O O, Fig. 3. Fig. 11 is a top view of the front end of the shaper and tension-spring frame. Fig. 12 represents a cross-section of 95 the same on the line 12 12, Fig. 11, and Fig. 13 a longitudinal section on the line 13 13, Fig. 11. Fig. 14 represents a like section through one of the shapers, showing the lat-

ter inverted for making cigarettes. Fig. 15 is a face view of a shaper adapted for making cigarettes and cigar-bunches. Fig. 16 represents a central cross-section of the latter; and Fig. 17 is a fragmentary elevation corresponding in part with part of Fig. 13, showing an adjustable stop, as hereinafter set forth.

Like letters of reference indicate corresponding parts in the several figures.

10 Figs. 1, 2, 3, and 4 are drawn to one and the same small scale, and Figs. 1^a, 1^b, 3^a, 3^b, and 5 to 16, inclusive, are drawn to one and the same larger scale.

15 I have shown in the drawings a machine adapted to roll twelve cheroots, cigarettes, or cigar bunches at each operation, with its rolling-aprons A, shapers S, and tension-springs T, and their individual appurtenances in two "longitudinal" series of six each, extending 20 from front to rear, with its bed-frame B mounted upon the top of an ordinary work-bench, W, and with a counter-weight, C, treadle T², and connecting-cords C' C² as operating accessories, the latter running over pulleys P' P², 25 attached respectively to the ceiling of the room and to said work-bench.

The machine may be adapted to roll more or less than twelve at one operation. Its capacity may be increased or diminished by arranging more or less than six sets of rolling devices in each series, or by making the machine with more than two or but one series. The series may extend from right to left instead of from front to rear. Different operating accessories may be employed without departing from the spirit of this invention, and details of construction not essential to my respective combinations of parts hereinafter claimed may be modified or changed at will; but for convenience and perspicuity the following description will be confined, with one or two exceptions, to the machine as shown. Said aprons A, one of which is shown separately by Figs. 5 and 6, are preferably of rubber cloth, and each 45 has a metallic cross-bar, C², attached to one end by rivets, said cross-bar being triangular in cross-section, so as to transmit the pulling strain to the apron equally. The apron may either be attached, as shown, to that side of 50 the cross-bar which is its front in action, as seen in Figs. 3, 3^b, and 14, or to its back, and re-enforced by a keeper-strip, k, of metal, as shown in Fig. 6^x, which also illustrates a different triangular shape for the cross-bar. At 55 its other end each apron is tacked fast upon the top of one or the other of two longitudinal "rolling-beds," R, forming part of said bed-frame B, the whole of which is preferably wooden.

60 For simultaneously "pulling" said aprons through the medium of said cross-bars in the rolling operation, the machine is provided with a pulling-frame, F, the rear end of which is shown separately in Fig. 9, as aforesaid. This 65 is a metallic frame, its main members being four longitudinal pull-rods, R², which slide in grooves in said rolling-beds, as best seen in

Figs. 7, 8, and 10, and are provided with inclined stud-pins or hooks h, which engage with notches n in the ends of the cross-bars C², holding them down to their work while the aprons are pulled by said slide. (See Figs. 7 and 8.) A rod, R³, below the rolling-beds parallel with said pull-rods R², is embraced by a spiral retracting-spring, S³, Figs. 1, 2, 3, and 75 10, which reacts between the rear cleat of the bed-frame B and a cross-pin, c³, applied to said rod R³. Said rods are all connected at their rear ends to a cross-bar, C⁴, having a central depending lug, l, Fig. 9, to engage 80 with said rod R³ and a pair of rings, r, Fig. 9, to which said cords C² are connected. Said rods R² are connected with said cross-bar C⁴ by pairs of pins p, Fig. 9, occupying perforations in the ends of the rods, those p² in 85 the outer rods being multiplied to provide for taking up the aprons at their outer edges more or less in rolling cheroots. The shapers S and tension-springs T are strung upon three longitudinal guide-rods, G, of metal, 90 parallel with each other, which form part of said shaper and tension-spring frame F. The other parts of this frame, which are shown in detail on Sheet 4 of the drawings, are three wooden bars fitting between and on each outer 95 side of the rolling-beds R, and connected with the rear cleat of the bed-frame B by hinges h', Figs. 1 and 3, and a cross-bar, C⁵, at the front end of the frame, together with an eye-ring, e', Fig. 11, at the middle of said cross-bar C⁵, 100 to connect with the cord C', brackets b', Figs. 11 to 13, supporting said guide-rods G at their ends, and cross-pins c' locking said guide-rods in place, forming abutments for the respective tension-springs, and limiting the reaction 105 of the latter, all of said pins being held in perforations in said guide-rods. Said tension-springs T, being individually supported by cross-pins c', as shown, serve to cushion the 110 respective shapers, so as to insure uniformity in the degree of compression applied to the tobacco within the bights of the several aprons, and thus to insure uniformity of density or tightness in each kind of product, as aforesaid. As the middle series of springs 115 have double work to do as compared with those on the outer guide-rods, the former are made of double weight, as represented.

Different machines may be provided with springs of different degrees of strength for 120 varying the product, or adjustable stops may take the place of said cross-pins c'. One such adjustable stop, c^x, is shown in Fig. 17. It consists of a loose collar provided with a thumb-screw, by which it is readily clamped 125 on the guide-rod G, to which it is applied, so as to form an abutment for the coacting tension-spring T at any desired point. Each of said shapers S has its ends e bored cylindrically to work steadily on said guide-rods, and 130 in diagonally-opposite edges of a rectangular body it has cavities e' c', Figs. 11 to 14, extending lengthwise thereof, and adapted, respectively, for shaping cheroots and cigarettes,

or it may be cavities c^2 b , Figs. 15 and 16, adapted, respectively, for shaping cigarettes and cigar-bunches. All said shaper-cavities have rounded ends to facilitate polishing their walls and to preclude any binding of the edges of the aprons therein. Said cavity c tapers from end to end correspondingly with cheroots. Said cavities c^2 are each adapted to shape double-length cigarettes, which are cut in half for the market. Said cavity b is of uniform shape and dimensions between its rounded ends, or it may be of any other shape suitable for shaping cigar-bunches. The effective cavity of each shaper is its lower cavity for the time being. This is said cavity c in the machine, as shown by Figs. 1 to 13, inclusive.

Fig. 14 illustrates the inversion of the same series of shapers S to produce cigarettes, and Figs. 15 and 16 illustrate the employment of a second series of shapers, S^2 , which is the only addition required to adapt the machine for making cigar-bunches, as well as cigarettes and cheroots.

To prevent any interference of said shapers with the aprons A working beneath them, said rolling-beds R are provided between said pull-rods R^2 and the edges of the aprons with longitudinal track rods or wires t , Figs. 2, 4, 7, and 10, pinned fast thereon, upon which said shapers S , as well as said cross-bars C^2 of the aprons ride smoothly. (See Fig. 10.)

In operation, said shaper and tension-spring frame F^2 being in elevated position, as represented in Figs. 1 and 2, and the aprons A flat, as represented by the right-hand series seen at the top in Fig. 2, and further illustrated by Fig. 1^a, the operator (or a special expert) places upon each apron in proper position a wrapper, and thereon the proper quantity of tobacco for a cheroot, for example. The cross-bar ends of the aprons are now turned back over the tobacco thereon, and the cross-bars C^2 are successively engaged with the hooks h , appropriate to each on said pull-rods R^2 , as illustrated by the left-hand series of aprons seen at the bottom in Fig. 2, and further illustrated by Fig. 1^b. Said frame F^2 is now lowered, bringing the several shapers down above the respective aprons, between their cross-bars and the bight of each apron containing the tobacco, as seen in Figs. 3 and 4 apart from dotted lines in the former figure, and further illustrated by Fig. 3^a. The weight of a hand on the lowered frame suffices to hold it down solidly; but it may be fastened down by a hook or the like, if preferred. The operator now depresses the treadle T^2 with his foot, and thus, without hand-work, with the aid of said cords and pulleys $C^2 P^2$ (a set at each edge of the treadle,) acts on said pulling-frame F , and therethrough on all said cross-bars C^2 and every apron A simultaneously, drawing the bight of each apron into the opposing cavity c of the corresponding shaper, S , and rolling its contents within said bight and partly within said cavity to the requisite extent. At

the end of this operation, reached in a moment, the parts occupy the positions represented by dotted lines in Fig. 3, and by the diagrammatic edge view, Fig. 3^b, the shapers having shifted under the pulling-strain to a distance something less than half that traversed by the cross-bars C^2 , the tension-springs T resisting their displacement to the proper extent to insure the desired density in the product, as aforesaid. The treadle T^2 is held down a moment longer while said frame F^2 is thrown up to its elevated position, the shapers thereon returning to their original positions, respectively, under the reaction of the tension-springs. When the treadle is released, the retracting-spring S^2 , condensed by the projection of the pulling-frame F , restores said frame to normal position and re-elevates the treadle preparatory to the next rolling operation. The several aprons are now straightened out and the rolled cheroots are removed therefrom, each being provided with a fresh wrapper, which is supplied with tobacco, the apron turned back over it, and so on, as before.

To convert the machine for cigarette-making, it is only necessary to take out the cross-pins c' from the guide-rods G , remove the shapers S and springs T , and replace them with said shapers inverted, as shown in Fig. 14; and to convert the machine for making cigar-bunches it is only necessary to strip said guide-rods and replace the parts with shapers S^2 , Figs. 15 and 16, having cigar-bunch cavities b in place of said shapers S .

Having thus described my said improvement in cheroot, cigarette, and cigar bunch machines, I claim as my invention and desire to patent under this specification—

1. In a machine for making cheroots, cigarettes, or cigar-bunches, the combination, substantially as herein specified, of one or more rolling-beds, one or more series of rolling-aprons, shapers crossing said aprons, and tension-springs parallel with said aprons, said aprons being attached to said beds at one end of each apron and provided with cross-bars at their free ends, and a pulling-frame adapted to engage with said cross-bars for pulling the several aprons simultaneously, for the purpose set forth.

2. The combination, substantially as herein specified, of one or more rolling-beds, one or more series of rolling-aprons, shapers crossing said aprons, and tension-springs parallel with said aprons, said aprons being attached to said beds at one end of each apron and provided with cross-bars at their free ends, a pulling-frame in the plane of said beds to coact with said cross-bars, and a shaper and tension-spring frame carrying said shapers and tension-springs and adapted to be elevated while making ready for the rolling operation.

3. The combination, substantially as herein specified, of one or more rolling-beds, one or more series of rolling-aprons attached to said beds at one end of each apron and provided with cross-bars at their free ends, a pulling-

- frame to coat with said cross-bars, and a shaper and tension-spring frame provided with shapers, and tension-springs applied to said shapers, said shapers being arranged to correspond with the respective aprons and constructed with matrical cavities to receive and coat with the tobacco-containing bights of the aprons for shaping the product with uniformity, in the manner set forth.
10. 4. The combination, substantially as herein specified, of one or more rolling-beds, one or more series of rolling-aprons attached to said beds at one end of each apron and provided with cross-bars at their free ends, a pulling-frame to coat with said cross-bars, and a shaper and tension-spring frame provided with longitudinal guide-rods, and series of shapers and tension-springs thereon corresponding with said series of aprons, each tension-spring being proportioned to its work and supported longitudinally independently of the others for equalizing the density or tightness of each kind of product.
15. 5. In a machine for making cheroots, cigarettes, or cigar-bunches, the combination, with rolling-aprons, of transverse reversible shapers, each constructed with diagonally-opposite matrical cavities lengthwise thereof, one of said cavities being adapted to shape cheroots or cigar-bunches and the other to shape cigarettes, substantially as herein specified.
20. 6. The within-described reversible shapers, each constructed with diagonally-opposite matrical cavities lengthwise thereof, and cylindrically-bored ends, one of said cavities being adapted to shape double-length cigarettes, in combination with rolling-aprons extending substantially at right angles to said shapers, and guide-rods parallel with said aprons fitted to the bores in the ends of the shapers, substantially as specified.
25. 7. In combination with one or more rolling-beds, and a pulling-frame in the plane thereof, one or more series of rolling-aprons attached to said beds at one end of each apron, and provided at their free ends with metallic cross-bars, triangular in cross-section, attached to the aprons along the entire edge of each and 30 coating with said pulling-frame, substantially as herein specified.
35. 8. In combination with one or more rolling-beds and one or more series of rolling-aprons attached to said beds at one end of each apron, and provided at their free ends with metallic cross-bars triangular in cross-section and having notched projecting ends, a pulling-frame having longitudinal pull-rods provided with
- stud-pins or hooks adapted to fit said notched ends, and projecting obliquely in the direction 60 of the rolling movement and serving to hold down the cross-bars to their work, substantially as herein specified.
9. In combination with a pair of rolling-beds parallel with each other, and two corresponding series of rolling-aprons, shapers crossing said aprons, and tension-springs parallel with said aprons, said shapers provided with outwardly-tapering cavities for shaping cheroots, a pulling-frame and means for connecting said frame with said aprons, said frame comprising longitudinal pull-rods and a cross-bar to which the power is applied, and having an adjustable connection between said cross-bar and the outer pull-rods, substantially 75 as herein specified, for the purpose set forth.
10. One or more rolling-beds provided with longitudinal track-rods pinned fast thereto, in combination with one or more series of rolling-aprons attached to said beds at one end of each apron and provided at their free ends with cross-bars, means for pulling the same, and a corresponding series of shapers arranged to coat with said aprons and supported out of interfering contact therewith by said track-rods, substantially as herein specified.
11. The combination of two or more rolling-beds parallel with each other, corresponding series of rolling-aprons, shapers crossing said aprons, and tension-springs parallel with said aprons, a pulling-frame common to all, comprising two or more pairs of pull-rods, and a cross-bar common to all, means for connecting said pulling-frame with said aprons, and a shaper and tension-spring frame comprising 90 longitudinal frame-pieces, which carry said shapers and springs, united by a cross-bar, substantially as herein specified.
12. The combination of one or more rolling-beds, one or more series of rolling-aprons, shapers crossing said aprons, and tension-springs parallel with said aprons, a pulling-frame common to all said aprons, means for connecting said pulling-frame with said aprons, a shaper and tension-spring frame, which carries all said shapers and springs, a treadle and connections and a retracting-spring for actuating said pulling-frame, and a counter-weight and connections for elevating said shaper and tension-spring frame, substantially as herein 105 specified, for the purpose set forth.

JOHN S. GOLDSMITH.
